JEREMIAH RHOADS, OF NILES, MICHIGAN.

Letters Patent No. 99,476, dated February 1, 1870.

IMPROVED CLAMP FOR FORMING HORSESHOE-CALKS.

The Schedule referred to in these Letters Patent and making part of the same

To all whom it may concern:

Be it known that I, JEREMIAH RHOADS, of Niles, in the county of Berrien, and State of Michigan, have invented certain Improvements in Clamps for Use in Forming Calks on Horseshoes, of which the following is a specification, reference being had to the accompanying drawings.

My invention consists in a clamp or swage, to be applied to an anvil, for holding horseshoes while having the calks formed on them.

In the drawing—

Figure 1 is a top plan view of my clamp, with a shoe in position therein, and

Figure 2 is a longitudinal vertical section of the same, on the line $x-x$ of fig. 1.

In constructing my clamp, I first provide a solid metal block, A, provided, on its under side, with a stud, a, to be inserted in a hole in the anvil, to hold the device in position, and having one of its upper edges, b, bevelled or chamfered off, as shown in both figures.

Into the opposite end of the block A from that having the bevel, I screw a strong metal eye-bolt, B, and through this eye-bolt pass one end of a stirrup or link, C. This stirrup is of a shape corresponding to that of the block A, and of a size to permit of its being shut down over and around the block, and leave a space between it and the front end of the block equal to the thickness of the horseshoe.

In using my device, the stirrup is raised, as shown in dotted lines, and the shoe placed against its front end, with the ends projecting above the face of the block.

The stirrup is then driven down over the shoe, as shown in figs. 1 and 2, thus locking the shoe rigidly to the block. The ends of the shoe are then bent over, as shown in fig. 2, and hammered down on the bevelled face b until the requisite edge is obtained, as shown in dotted lines in the same figure. The stirrup is then driven up, and the shoe released.

The shoe is then turned over, and the toe-calk, which has been previously welded on, treated in a similar manner.

A little hardy, E, may, if desired, be inserted in the top of the block A, for trimming the calks or other portions of the shoe.

After lifting up the stirrup C, it may be turned, so as to screw the eye B into or out of the block, and thus leave more or less space between the end of the block and the stirrup, so as to accommodate shoes of different thicknesses.

Having thus described my invention,
What I claim, is—

1. A clamping-swage, consisting of the block A and the stirrup or clamp C, constructed and arranged to operate substantially as described.

2. The combination of the die or block A, the stirrup or clamp C, and the adjustable eye-bolt B, all constructed and arranged as set forth.

JEREMIAH RHOADS.
